Specification of Letters Patent. Patented Apr. 18, 1922.

Application filed December 10, 1915. Serial No. 66,195.

To all whom it may concern:

Be it known that I, WILLIAM W. CAMERON, a resident of La Crosse, in the county of La Crosse and State of Wisconsin, have invented 5 certain new and useful Improvements in Plows, of which the following is a full, clear, and exact description.

This invention relates to traction plows.

One object of the invention is to provide 10 an improved power lift for the plow in which the plowing structure is sustained upon a rotating shaft provided with shifting connections between the shaft and the plow carrying structure for raising and lowering the latter, the shaft being sustained between two 15 of the ground wheels in such a way that the raising and lowering of the structure by the connection will cause the said ground wheels to shift so as to increase the upward and 20 downward movement of the structure.

Another object of the invention is to provide 25 improved means for raising and lowering the plow carrying structure so that the plow may be locked in its raised and in its lowered positions with means for setting the 30 mechanism into automatic action by the engine driver by the operation of a single lever pulled in the same direction for all operations.

Another object of the invention is to secure 35 a differential shifting of the forward sustaining wheels by novel means whereby the plow carrying structure will be approximately level transversely when in its raised and in its lowered positions.

Another object of the invention is to control 40 the position of the rear end of the structure by the position of the differential shifting mechanism of the forward wheels and lock the rear wheel against castoring while plowing and automatically release the lock by the vertical rise of the plow to permit of free castoring while the plow is being transported.

Another object of the invention is to provide 45 power operated plow shifting mechanism which is simple in construction and inexpensive in production.

The invention consists of several novel 50 features hereinafter set forth and more particularly defined by claims at the conclusion thereof.

In the drawings Fig. 1 is a plan of the plow embodying the invention.

Fig. 2 is a side elevation seen from the 55 plowed ground side of the plow.

Fig. 3 is a side view of the plow seen from its land side or unplowed ground side.

Fig. 4 is a front elevation with the plows and rear wheel attachments omitted. 60

Fig. 5 is a diagram showing the relative positions of the plow beams, the eccentric, the free end of the crank arm with its spindle in the landside sustaining wheel when in plowing position, all shown in full lines; the 65 dotted lines showing the relative position the parts would assume if the beams were raised by the eccentric alone; the lifting levers and controlling mechanisms being omitted.

Fig. 6 is another diagram with the controlling levers etc. in position, the full lines showing the parts in plowing position and in the same position as indicated in Fig. 8; the dotted lines showing the position the parts assume when raised by both the eccentric and the shifting of the landside sustaining wheel. 70

Fig. 7 shows the hand lever for shifting the front furrow wheel by hand, the ratchet to which it is locked, the block pivoted to the 80 continuously rotating shaft 11, the lever bar rigid to the ratchet and slidingly connected to the plow beam on the furrow side of the plow and a section of the beam to which it is connected.

Fig. 8 shows a similar view of the same parts on the landside of the structure, the block pivoted to the shaft and rigidly secured to the ratchet being prolonged into an arm for controlling the rear wheel mechanism. 85

Fig. 9 shows the rear wheel controlling device when the rear of the plow is in lowered position.

Fig. 10 shows the same parts in the position assumed when the rear of the plow is in its raised position. 95

Fig. 11 is a detail of the clutch mechanism taken on line *a—a* of Fig. 1 looking toward the landside of the plow, separate parts being shown in cross section but with the clutch dog and dog shifting lever in full lines, the lever being shown in inclined position to force the dog into the revolve clutch. 100

Fig. 12 is a view of the same parts, with the clutch mechanism turned half way around, with the dogs free from the clutch and in reversed position and with the eccentric itself also in reversed position.

Fig. 13 is a detail of parts shown on lines *b*—*b* of Fig. 10.

Fig. 14 is a detail showing a top view of a socket attachment at the landside end of 10 the continuously rotating shaft for turning the shaft by hand with a bar.

In the drawings 1 indicates the plows, mounted upon plow beams 2, the beams being rigidly connected to form a unit by the 15 U-shaped cross-bar 3 in front and cross-bars 2^b at the rear so that the plow carrying structure with the plows are shifted together. 3^a and 3^b are clevis jaws to which the draft bar is attached. 4 is a front carrying wheel 20 on the furrow side of the plow, 5 a land wheel on the opposite side, both being placed toward the front end of the structure. 6 is the rear carrying wheel mounted upon a shank 6^a, having a bearing in the rear of the 25 part 32 pivoted to the structure for vertical swinging.

7—8 indicates a crank arm pivotally mounted at its inner end upon a continuously rotating shaft 11, its front end 8 being provided with a spindle sustained in the hub of the wheel 4.

9—10 shows the same relative parts on the opposite side.

10^a indicates a sprocket and chain driving 35 mechanism between the wheel and the shaft 11 on the landside, and 10^b indicates a chain and sprocket driving mechanism between the furrow wheel and shaft 11, on the furrow side, the continuous rotation of the wheel 40 on each side causing the shaft 11 to rotate continuously in the same direction the wheels travel.

12 indicates springs at each end of the 45 shaft 11 for keeping a toothed clutch mechanism between the sprocket wheels and the shaft 11 in constant operable connection in driving forward, but permitting the machine to be pushed backwardly without rotating the shaft 11. Inasmuch as this is a 50 usual mechanism and forms no part of my invention it is not shown in detail.

13 indicates a clutch wheel rigidly secured by a key or other device to the shaft 11 and constantly rotating with it, and provided with recessed apertures 13^t. Partially covering both sides of the clutch wheels are two halves of a casing 18, which are alike except being rights and lefts, with inwardly projecting parts which meet and are rigidly 60 united by the tie-bolts 18^k to form a rigid casing. This casing is pivoted on the shaft 11 on each side of the wheel 13 and has two radial arms, 18^t being oppositely spaced and provided with enclosing springs 18^d surrounding the dogs 14; by means of the pins

18^e through the dogs the springs normally keep the dogs forced away from the apertures 13^t in the clutch wheel 13, with their outer ends projecting over the looped guide bar 18^g as indicated at the left hand side of 70 Fig. 11 and both sides of Fig. 12. The guide is on the rear sustained upon a bracket 17 attached to the casing 19 of the landside eccentric, and the forward end is attached to a cross-bar 16 extending between the two clevis 75 jaws 3^a and 3^b and bolted thereto as shown in Fig. 4.

A dog shifting lever 15 is pivotally supported at 15^a upon a bracket 15^c attached to the landside clevis jaw 3^b. See Fig. 4. 80

When in normal plowing position the right hand dog 14, Fig. 11, is over the forward end of the guide 18^g. It is manifest that in that position with the inner end of the dog out of the opening 13^t it will be impossible for the casing 18 to rotate forwardly or operatively, as the dog would immediately strike the end of the guide; neither could it revolve backwardly as immediately the opposite dog would strike the 90 rear end of the guide 18^g; but in Fig. 11 the dog shifting lever 15 has been tilted forwardly somewhat by the pulling of the cord 45 by the engineer, the lower end of the lever has forced the dog inwardly into one of the apertures 13^t with its outer end far enough in to be free to pass the end of the guide and slide along its inner face to keep the dog in the aperture while the shaft 11 and the casing 18 with the tie-bar 19^e are making half 95 of a revolution about the center 19^d of the eccentric disc 19^b described below.

The spring cannot force the dog out of the opening 13^t until it has passed the end of the guide, when it will withdraw from the aperture and be forced into the position shown at the left hand of Fig. 12. Meanwhile the opposite dog has also traversed a half revolution and comes into the position indicated at the right hand side of Fig. 12, the power 110 of the spring 18^a being sufficient to force the loosely pivoted lever 15 into a practically vertical position again. When the lever 15 is operated to shift the dog into the clutch, a small projection 15^b at the lower end of the 115 lever contacts against the cross-bar 16 to prevent it moving further than is enough to force the dog properly into the opening 13^t and free of the end of the guide.

In making this half revolution the tie-bar 120 19^e connecting the two eccentric discs 19^b is brought to the upper position over the center and the shaft 11 is brought to the lower position beneath the center of the eccentric.

In the position shown in Fig. 12 the plowing structure has raised as far as the eccentric will carry it. It is manifest that the parts will remain in this reversed position until the lever 15 is again pulled forward by the engineer when the process will 125 130

be repeated in another half revolution and the parts return to their original position with the plow in lowered position for plowing. The loop guide 18^a is bolted to its brackets with plow bolts 18^b, the heads of which are countersunk in the inner face of the guide.

Attached to the forward ends of the plow carrying structure upon opposite sides are 10 the brackets 19 connecting the structure with the continuously rotating shaft 11 by means of the eccentric discs 19^b. This construction is more fully shown in Figs. 4, 5 and 6. The parts 19 on each side are in pairs 15 and held together by bolts as indicated, with a circular opening in each part and having an enlarged annular groove as shown in the cutaway portion on the right hand side of Fig. 4, these grooves enclosing the periphery of the eccentric discs 19^b, also indicated by the dotted lines 19^a in Fig. 5. The discs 19^b are oppositely perforated at equal distances from the center for the passage of the tie-bar 19^c connecting the two discs, and 20 the shaft 11 which extends through both eccentrics and outwardly to be driven by sprocket and chain connections with the two ground wheels, as shown in Figs. 1, 2, 3 and 4.

30 The eccentric discs being contained in the brackets 19 rigidly attached to the beams, it is manifest that the centers of the eccentrics will always be at a fixed distance from the beams. The tie-bar 19^c passing through the clutch casing arm 18^b, the movement of the tie-bar caused by the dogs entering the apertures 13^c transmits rotary motion to the eccentrics which revolve about their centers; and as the shaft 11 so far as the operation 40 has been described is stationary with relation to the ground, it is manifest that the whole eccentric rotates about the axis of the shaft 11 and the eccentric causes the plow beams to be raised a distance equal to 45 the distance between the axes of the shaft 11 and the tie-bar 19^c, although in so doing the eccentric disc and the bar and shaft also rotate about the eccentric center. The amount of rise contributed by the eccentric 50 mechanism is clearly indicated in Fig. 5 (in which for the sake of clearance other contributing mechanism is omitted) by the dotted lines.

20 indicates a ratchet on the landside of the machine rigidly attached to the lever arm 21, which in turn is rigidly secured to the arm 23, the latter being pivoted on the shaft 11 (see Fig. 8) in which the hand lever 25 is indicated in dotted lines. The 55 hand lever 25 is pivotally supported on the shaft 11 by the base 25^a, which is a part of the crank arm 9—10 carrying the wheel 5 at its free end; the hand lever with its crank arm and the ratchet and arm 23 thus being 60 concentric with the shaft 11. The hand le-

ver may be adjusted to various positions on the ratchet, thus shifting the wheel 5 and raising the shaft 11 vertically with relation to the axis of the wheel 5. The angled lever arm 21 to which the ratchet 20 is rigidly attached extends rearwardly and slidingly through a slotted bracket 22 that is rigidly attached to the beam as shown in Figs. 3, 6 and 8. The three parts, the ratchet 20, the arm 21 and the arm 23, also the 70 lever 25 with the crank arm 9—10, therefore always act as a unit in shifting the plow carrying structure with relation to the axis of the wheel 5 except when the wheel is manually shifted by the hand lever. In 75 Fig. 1 the hand lever is shown in cross section. This hand lever and the one upon the opposite side is provided with the usual means for locking the same in adjusted positions to the ratchet. The free end of the 80 arm 23 is connected to the forward end of the connecting bar 24 that at its rear attaches to and operates the mechanism for raising and lowering the rear end of the structure simultaneously with the front end. 85

Upon the opposite or furrow side of the plow for controlling the relative positions of the furrow wheel, similar parts are connected together, the hand lever being indicated by the numeral 26, its support upon 90 the crank arm 7—8 by 26^a, the ratchet by 95 27, the lever arm by 28, the arm 28^a pivoted on the shaft 11 being cut off where it is attached to the bar 28 instead of being prolonged as in 23. The slotted bracket 29 100 through which the rear of 28 passes is attached to the furrow side beam as shown in Fig. 7. In all respects the location of the parts is similar to those of the opposite side except that the slotted bracket 29 is 105 placed further in the rear from the shaft 11 with which the ratchet 27 moves concentrically, and the lever bar 28 is necessarily longer than the bar 21; see Figs. 2 and 7.

In Figs. 1, 2, 3 and 4 the land wheel 5 110 is represented as being on the surface of the ground with its axis horizontally in front of the shaft 11 by resting upon a block A, while the furrow wheel 4 is shown as being on the bottom of the furrow, on a level 115 with the bottom of the plows, the hand lever 26 being shown as adjusted accordingly.

In Fig. 6 the land wheel spindle 10 is represented as horizontally in front of the shaft 11, and the ratchet bar 21 and other united 120 parts with the eccentric bracket 19 and enclosed eccentric disc of the landside are shown in full lines to indicate plowing position; while the dotted lines show the position the parts assume when raised as in 125 actual practice by the combined effect of the raise by the eccentric and the shifting of the land wheel 5; for it is manifest that as the plow carrying structure is raised by the rotation of the eccentric as indicated by 130

dotted lines in Fig. 5, the arm or lever bar 21 is carried upwardly with it by the slotted bracket 22, thus rotating the ratchet 20 and arm 23 about the shaft 11 and with it 5 the hand lever 25 and the crank arm 9—10, thus drawing the wheel 5 backwardly and raising the shaft 11 with the same effect in raising the structure as if the hand lever were operated by hand and giving an additional elevation of the plow carrying structure. Inasmuch as the eccentric center is in a fixed position with relation to the beam, the shaft 11 and tie-bar 19^c are not only reversed as shown in Fig. 5 but the shift of 15 the wheel 5 raises the shaft 11 to the position indicated by the dotted lines in Fig. 6. In the diagram of Fig. 5 the shaft 11 remains stationary while the eccentric rotates and carries the tie-bar 19^c above the shaft 20 but in Fig. 6 the combined effect of both means of shifting the plow carrying structure is shown with a largely increased elevation of the plow beam 2.

The amount of additional rise caused by 25 the shifting of the ground wheel will depend upon the leverage obtained by the distance the slotted bracket is placed rearwardly from the axle 11. Inasmuch as when the plows are at work in the ground the structure is approximately and transversely level, and would be out of level when raised without some adjustment, the slotted bracket 29 is placed further back from the shaft 11 than is the bracket 22; and while bracket 29 35 is elevated the same distance by the eccentric as is 22 it has less effective leverage and the wheel 4 is not shifted as much as is the wheel 5, and consequently it does not assist in raising its side of the plow so much as does 40 22, with the effect of tending to maintain the lever of the plow carrying structure when coming out of the ground.

At the rear of the structure the wheel 6 rotates on the shank 6^a, the vertical portion 45 of which passes through the bracket 32 to castor freely when not locked against it. The bracket 32 is pivoted for vertical movement at 35 on the bracket plate 30 rigidly attached to the rear beam 2. The rear of 50 the plate 30 is concentrically curved to correspond with the curve 32^a of the pivoted bracket 32 where it and the bracket 32 coincide. Pivoted on the hinged bracket 32 at 55 39 is a strap 34, the upper end of which is pivoted to the bell crank lever 31 at 40, which in turn is pivoted to the bracket plate 30 at 41. The free end of 31 is pivoted to the rear end of the connecting bar 24, so that when the arm 23 is rotated forwardly by 60 60 the elevation of the lever arm 21 the bell crank lever 31 is rotated forwardly upon its pivot 41 causing a downward pressure upon the strap 34 and imparting a rotary movement to the bracket 32 upon its pivot 35. 65 32 is supported on the shank 6^a by the col-

lar 33 rigidly secured to same by the pinch bolt 38. See Fig. 13. The parts and the rear wheel are shown with the plow in a lowered position in Fig. 9. Inasmuch as 70 32 is pivoted at 35 to the plate 30 the effect 75 of the movement is to swing the shank 6^a about the pivot 35 and bring the wheel closer to the plow; that is, there is an effective leverage extending between the pivot 35 and the axis of the wheel 6 so that as the wheel is drawn forward the shank by its collar 33 raises the bracket 32 and with it the plate 30 and the plow, as shown in Fig. 10. When in the lowered position shown in 80 Fig. 9 the rear bottom corner edge of the 85 plate 30 rests in an open slot 36 in the forward portion of the collar 33 as shown in Fig. 13 and in Fig. 9, and effectively prevents the shank 6^a from castoring in the bracket 32. But as an effect of the combined leverage of the parts 31 and 32 and 90 34 the rear of the plate 30 rises faster than the collar 33 and the corner of the plate 30 rises above the locking slot 36, and in the raised position of the plow the shank and 95 wheel are free to castor. This is desirable in transportation of the plow in turning corners, while in plowing operations, especially with tractor-drawn plows, it is found desirable to keep the wheel rigidly in line with the direction of travel and locked against castoring.

The upper plate portion of the collar 33 is made with quite a large upper bearing surface extending horizontally and circumferentially to the limits of the turning of the shank 6^a in its bearings in the bracket 32, so that should an effort be made to lower the plow while the wheel is turned out of its proper locking position the plate 30 cannot lower outside of the extension in which the slot 36 is formed and lock the shank and wheel against returning to their proper position. (See Fig. 13.)

To keep the rear of the bracket 32 and 110 the collar 33 in proper adjoined position and yet permit the free turning of the shank and collar in the bracket, a hook portion 37 is formed at the rear of the collar to embrace an extending rim at the lower end of the 115 rear of the bracket 32 as shown in Figs. 9 and 10 and indicated in Fig. 13 in cross section.

In operation, with the plow traveling forward in the ground, when it is desired to 120 raise the plows from the ground the tractor driver pulls the cord 45, which pulls the upper end of the lever 15 forwardly, the lower end of which forces the forward dog backwardly into one of the openings in the 125 clutch wheel 13 with the forward end of the dog free to slide along the inner face of the guide 18^a, thus turning the casing 18 and causing the tie-bar 19^c to rotate the eccentric discs 19^b about their centers and within 130

the grooves of the brackets 19 and raise the plow carrying structure; and the raising of the beams thereof causes the lever arms or bars 21 and 28 to rotate the ratchets 20 and 27 and the levers 25 and 26 with their crank arms 7-8 and 9-10 to shift the wheels 4 and 5 rearwardly to lift the shaft 11 and with it increase the rise of the whole plow carrying structure and the connections from the shaft 11; at the same time rotating the arm 23 upon the shaft 11 and causing the connecting bar 24 to operate the bell crank lever 31 to shift the bracket 32 and bring the wheel 6 closer to the rear of the plow and raise the rear end thereof and lift the plate 30 out of the slot 36 so as to leave the shank and wheel free to castor in the bearing in 32. In its raised position with the tie-bar 19^a above the shaft 11 the dogs 14 in position above the ends of the guide 18^a will prevent the movement of the tie-bar in either direction and lock the eccentrics also against movement. When it is desired to lower the plow the operator again pulls the cord 45 when the whole operation is automatically reversed and the plows are brought again to proper lowered working position.

For convenience I designate the cranks 7-8 and 9-10 and the shaft 11 as a supporting structure, the beams and braces 2, 2^b and 3 as a plow carrying structure, and the eccentrics 19-19^b as the shifting connection between the two structures.

The mechanism herein described is very simple and very efficient and is very inexpensive in construction. While I have shown and described a very efficient embodiment of my invention it is to be understood that I do not limit the scope thereof to the precise structure shown, as many modifications thereof might be made without departing from the spirit of the invention and of the claims herein made.

Having thus described the invention, what I claim as new and desire to secure by Letters Patent is:

1. In a plow, a plow carrying frame, supporting wheels therefor, mechanism moving the frame with respect to the wheels, and supplemental mechanism acting automatically in conjunction with the first named mechanism for further moving the frame with respect to the wheels.

2. In a plow, a plow carrying frame, supporting wheels therefor at the front of the frame, means operated by one of said wheels for raising and lowering the front of the frame with respect to the wheels, and supplemental mechanism intermediate the frame and the wheels and operated by the frame to further raise and lower the frame with respect to the wheels.

3. In a plow, a plow carrying frame, a rotatable shaft, means for rotating the shaft,

a frame, a raising and lowering connection between the frame and the shaft, a crank arm pivoted at one end on the shaft, a supporting wheel supported on the other end of the arm, and a connection between the frame 70 and the crank arm and operated by the frame to oscillate the crank arm when the frame is raised or lowered by the rotatable shaft.

4. In a plow, a plow carrying frame, a 75 rotatable shaft, means for rotating the shaft, a plow carrying frame, a raising and lowering connection between the frame and the shaft, a crank arm pivoted on one end of the shaft, a supporting wheel supported on the 80 other end of the arm, and a connection between the frame and the crank arm and operated by the frame to oscillate the crank arm when the frame is raised and lowered by the rotatable shaft, and means automatically acting for locking the frame in adjusted 85 positions.

5. In a plow, a plow carrying frame, a rotatable shaft, means for rotating the shaft, a frame raising and lowering connection 90 between the frame and the shaft, a crank arm pivoted at one end on the shaft and carrying a ground wheel at its other end, a connection between the frame and the crank arm and operated by the frame to oscillate 95 the crank arm when the frame is raised and lowered by the rotatable shaft, and means automatically acting for locking the last named connection in adjusted positions.

6. In a plow, a plow carrying frame, 100 ground wheels therefor, a rotatable shaft, crank arms axially supported in the wheels and on the shaft respectively, means for rotating the shaft, means mounted on the shaft for holding the arms in adjusted positions, and shifting mechanism between the shaft and the holding means for oscillating the crank arms.

7. In a plow, a plow carrying frame, 110 ground wheels therefor, a rotatable frame supporting shaft continuously rotated by one of the wheels during the travel of the wheel, means on the shaft for shifting the frame with respect to the shaft, and a shifting connection between one of the wheels 115 and the frame and operable by the latter as it is being shifted for moving the wheels to further shift the frame.

8. In a plow, a plow carrying frame, 120 ground wheels therefor, a rotatable frame supporting shaft continuously rotated by one of the wheels during the travel of the wheel, means on the shaft for shifting the frame with respect to the shaft, a shifting connection between the wheels and the frame 125 operable by the frame as it is being shifted for moving the wheels to further shift the frame, and means controlled by the operator for throwing the connection between the shaft and the frame into and out of gear.

9. In a plow, a plow carrying frame, ground wheels therefor, a rotatable frame supporting shaft, a raising and lowering connection between the shaft and the frame, 5 a shifting mechanism between the wheels and the frame operable by the latter as it is being shifted for moving the wheels to further shift the frame, a driving connection between one of the wheels and the shaft 10 operable in all the moved positions of the wheel, and means controlled by the operator for throwing the first named connection between the wheels and the frame into and out of gear.
- 15 10. In a plow, a plow carrying frame, ground wheels therefor, a rotatable frame supporting shaft, means on the shaft for shifting the frame with respect to the shaft, means for operating the shaft, a crank arm pivoted on the shaft at each end thereof, the free ends of the arms being sustained in the wheels, and operative mechanism between the arms and the frame and operated by the latter when being shifted for differentially shifting the wheels for further shifting the frame.
- 20 11. In a plow, a plow carrying frame, ground wheels therefor, a rotatable frame supporting shaft, means on the shaft for shifting the frame with respect to the shaft, means for operating the shaft, a supplemental mechanism between the wheels and the frame and mounted on the shaft and operable by the frame when being shifted for 25 differentially shifting the wheels to further shift the frame.
- 30 12. In a plow, a plow carrying frame, ground wheels therefor, a rotatable frame supporting shaft, means for rotating the shaft, means on the shaft for shifting the frame, and means for automatically and 35 differentially shifting the wheels to further shift the frame.
- 40 13. In a plow, a plow carrying frame, ground wheels therefor, a rotatable shaft, means for rotating the shaft, means on the shaft for equally shifting the two sides of the frame, and mechanism operated by the frame when being shifted for further and 45 unequally shifting the sides of the frame.
- 50 14. In a plow, a plow carrying frame, ground wheels therefor, wheel operated means for vertically shifting the frame with respect to the wheels, and mechanism operated by the frame when shifted for differentially shifting the sides of the frame, comprising a supplemental connection of the frame with the wheels.
- 55 15. In a plow, a plow carrying frame, ground wheels therefor, a shaft, means for operating the shaft, a raising and lowering connection between the shaft and the frame, and means comprising a lever operated by the frame when raising and lowering for 60 further shifting the frame, and a connection 65 between the lever and one of the wheels.
16. In a plow, a plow carrying frame, ground wheels therefor, mechanism between one of the wheels and the frame for raising and lowering the latter, and mechanism for shifting one of the wheels to further shift the frame and operable by the frame while being shifted comprising a lever and a yielding connection between the lever and the frame, and a connection between the lever 70 and the wheel.
17. In a plow, a plow carrying frame, ground wheels therefor, wheel operated mechanism between one of the wheels and the frame for raising and lowering the 80 frame, and means for shifting one of the wheels to further shift the frame comprising a lever arm at the side of the frame, a connection between the lever and the frame and operated thereby when being 85 shifted, a crank arm pivoted on the frame with its free end sustained in one of the wheels and operative mechanism between the lever and the crank arm.
18. In a plow, a plow carrying frame, 90 sustaining wheels therefor, a raising and lowering connection between one of the wheels and the frame, automatic means for shifting one of the wheels to further shift the plow with respect to the wheel comprising 95 mechanism between the wheel and the frame and operable thereby including manually operated means for shifting the wheel independently of the operation of the automatic means.
19. In a plow, a plow carrying frame, ground wheels therefor, mechanism for vertically shifting the frame with respect to the wheels, and automatically acting means for shifting one of the wheels to further 105 shift the frame comprising a lever, means for operating the lever by the movement of the frame when shifted comprising a slotted bracket on the frame, a sliding connection between the bracket and the lever 110 and a shifting mechanism between the lever and the wheel.
20. In a plow, a plow carrying frame, ground wheels therefor, a shifting mechanism between one of the wheels and the frame, and mechanism for further shifting the frame by the movement of the frame when shifted comprising a crank arm sustained in one of the wheels and pivotally connected with the frame, manually operable means for shifting the crank arm and means for locking the same in adjusted positions, and mechanism for shifting the locking means comprising a lever connection between the same and the frame.
21. In a plow, a plow carrying frame, ground wheels therefor, mechanism for shifting the frame with respect to the 125

wheels, a supplemental mechanism acting automatically in conjunction with said first named mechanism for further moving the frame with respect to the wheels comprising 5 hand levers pivotally mounted on the plow having operative connections with the wheels, pivoted sectors for locking the levers in adjusted positions, and automatic mechanism for shifting the sectors comprising 10 levers secured to the respective sectors and differentially connected with the frame for differentially shifting the hand levers.

22. In a plow, a plow carrying frame, 15 ground wheels therefor, a shaft continuously rotating during the travel of the plow, a raising and lowering connection between the shaft and the frame comprising an eccentric mounted on the shaft, a breakable 20 driving connection between the eccentric and the shaft, and means for breaking said driving connection when the frame is raised and lowered.

23. In a plow, a plow carrying frame, 25 ground wheels therefor, a driving connection between one of the wheels and the shaft continuously operating during the travel of the wheel, mechanism for shifting the frame with respect to the shaft comprising 30 an eccentric having a breakable driving connection with the shaft and a connection with the frame, and means for breaking the driving connection with the shaft.

35 24. In a plow, a plow carrying frame, ground wheels therefor, mechanism for shifting the frame comprising a shaft continuously rotating during the travel of the plow, and an eccentric pivoted on the shaft, 40 a driving connection between the eccentric and the shaft, and mechanism operated by the movement of the frame when shifted for simultaneously raising and lowering the eccentric and the shaft comprising supplemental mechanism between the frame and 45 one of the wheels.

25. In a plow, the combination of carrying wheels and a plow carrying frame, with power driven mechanism for shifting the 50 plow carrying frame comprising a shaft and a pair of eccentrics mounted on the frame and pivotally sustained on the shaft for simultaneously and equally shifting both sides of the frame, and means operated by the frame for simultaneously and 55 unequally raising the sides of the frame.

26. In a plow, the combination of carrying wheels and a plow carrying frame, with means operated by one of the wheels for 60 vertically and equally shifting the two sides of the frame and means operated by the frame when shifted to shift the wheels to additionally and unequally shift the two sides of the frame.

65 27. In a plow, the combination of carrying

wheels and a plow carrying frame, with power driven means for shifting the frame comprising a shaft and an eccentric mounted on the frame and pivoted on the shaft at a point radially spaced from the center 70 of the eccentric, an arm pivotally mounted on the shaft and connected to the eccentric at a point opposite the shaft and equally therewith spaced from the eccentric center, the shaft and the free end of the arm 75 rotating about the eccentric center in shifting the plow carrying frame.

28. In a plow, the combination of carrying wheels and a plow carrying frame, with mechanism for vertically shifting the 80 frame comprising a shaft and an eccentric pivoted on the shaft at a point radially spaced from the axis of the eccentric, a driving connection between the shaft and the eccentric with its free end connected to 85 the eccentric diametrically opposite the connection of the shaft therewith and equally spaced from the axis of the eccentric with both points of connection with the eccentric revolving about the axis thereof and the 90 eccentric revolving about the axis of the shaft, with means for throwing the connection into and out of gear with the shaft.

29. In a plow, the combination of carrying wheels and a plow carrying frame, with 95 mechanism for shifting the frame, comprising a shaft continuously rotating during the travel of the plow and an eccentric pivoted on the shaft, means on the shaft for rotating the shaft about the axis of the eccentric and 100 means for throwing the means on the shaft into and out of gear.

30. In a plow, the combination of carrying wheels and a plow carrying frame, with mechanism for shifting the frame comprising a continuously rotating shaft and an eccentric pivoted on the shaft, means on the shaft for rotating the shaft about the axis of the eccentric, means for throwing the means on the shaft into gear during shifting operations and out of gear when the 105 shaft has made a half revolution about the axis of the eccentric, and means for locking the eccentric against revolution when not engaged in shifting operations.

31. In a plow, the combination of carrying wheels and a plow carrying frame, with mechanism for shifting the frame comprising a shaft continuously rotating during the travel of the plow and an eccentric pivoted 120 on the shaft, means on the shaft for rotating the shaft a half revolution about the axis of the eccentric in shifting the frame in one direction and the other half of the revolution in shifting the frame in the opposite direction, and means for locking the shaft against revolution about the axis of the eccentric when not engaged in shifting operations.

32. In a plow, the combination of carrying 130

wheels and a plow carrying frame, with mechanism for shifting the frame comprising a shaft and an arm pivoted on the shaft, means on the shaft for operating the arm comprising a dog in radial relations to the shaft, means for shifting the dog longitudinally to engage the shaft and hold it engaged during the shifting operation, and means for releasing the dog when the shifting operation is completed.

33. In a plow, the combination of carrying wheels and a plow carrying frame, with mechanism for shifting the frame, comprising a shaft and an arm pivoted on the shaft, means on the shaft for operating the arm comprising a clutch and a dog in radial relations with the clutch and normally locked to hold the arm against rotation, manually operated means for shifting the dog inwardly to engage the clutch, a guide for holding the dog in engagement with the clutch during the shifting operation, and means for shifting the dog outwardly when the guide is passed to release the arm and engage the dog with a stop to prevent the arm from rotation backwardly.

34. In a plow, the combination of carrying wheels and a plow carrying frame, with mechanism for shifting the frame comprising a shaft and an arm pivoted on the shaft,

means on the shaft for operating the arm comprising a clutch wheel and a pair of dogs in radial relation to the clutch wheel and circumferentially spaced from each other, and means for shifting the dogs alternately to engage the clutch to raise and lower the plow carrying frame.

35. In a plow, the combination of front and rear carrying wheels and a plow carrying frame, with mechanism to raise and lower the front end of the frame comprising a shaft, an arm pivoted on the shaft and operatively connected with the rear carrying wheel, and a connection between the arm and the frame and operated by the rise and fall of the front end of the frame to shift the connection with the rear wheel.

36. In a plow, the combination of a plow carrying frame, front and rear carrying wheels, with means for raising and lowering the front end of the frame comprising a shaft and, means on the shaft operated by the rise and fall of the frame to increase the rise and fall of the front end of the frame and raise and lower the rear end of the frame.

WILLIAM W. CAMERON.
